ATTORNEY.

UNITED STATES PATENT OFFICE

HERBERT J. SOMERS, OF DETROIT, MICHIGAN

HUMIDIFIER

Application filed March 15, 1929. Serial No. 347,430.

My invention relates to a new and useful improvement in a humidifier adapted for use particularly with radiators and has for its object, the provision of means for humidifying the air in inclosed spaces, such as rooms, railway coaches etc. and which will be simple in structure, economical of manufacture and highly efficient in use.

Another object of the invention is the provision of a humidifier of this class whereby a maximum vaporizing may be effected with a structure of minimum size, thus resulting in a compact and durable arrangement.

Another object of the invention is the provision in a humidifier of this class of a reservoir or container having air tubes projected there-through and provided with automatically operated means for controlling the admission of water into the reservoir or container.

Other objects will appear hereinafter.

The invention consists in the combination and arrangement of parts hereinafter described and claimed.

The invention will be best understood by a reference to the accompanying drawings which form a part of this specification and in which,

Fig. 1 is a side elevational view of the invention.

Fig. 2 is a top plan view of the invention.

Fig. 3 is a view taken on line 3—3 of Fig. 2.

Fig. 4 is a view taken on line 4—4 of Fig. 2.

Fig. 5 is a view taken on line 5—5 of Fig. 3.

In the drawings, I have illustrated the invention mounted in super-imposed relation over an inclined radiator 9 having the steam inlet pipe 10 and the outlet pipe 11 communicating therewith. In the invention, I provide a reservoir or container 12 having a plurality of tubes 13 projected through the base 14 and extended inwardly of the container so as to terminate adjacent the upper edge thereof. Communicating with the steam inlet pipe 10 is a pipe 15 which is provided with the sinuous portions 16 and 17 so as to wind among the tubes 13 and form coils, this pipe

15 being connected by the pipe 18 to the outlet pipe 11. Secured to opposite sides of the container 12 by bolts 19, on which is threaded a wing nut 20, are supporting legs 21, each having an elongated slot 22 for the accommodation of the bolt 19. The angularly turned end 23 rests upon a plate 24 which is positioned on the radiator 9. The slots in the legs permit adjusting the height of the opposite ends of the container or reservoir 12 so that, while it is mounted on an inclined radiator 9, the reservoir may be mounted in horizontal position. Communicating with the interior of the container 12 is a water inlet pipe 25 in which is interposed the key controlled valve having the housing 26 and the needle valve 27. A float 28 is mounted on the end of the lever 29, this lever 29 being pivoted on the bell 30, which is mounted on the fitting 31 supported in the end wall of the container or reservoir. This fitting 31 carries at one end a valve seat 32 for engagement with the valve head 33 which is mounted on the rod 34, this valve head 33 being normally maintained in engagement with the seat 32 by the coil spring 35. An actuating member 36 is pivoted on the bell 30 and adapted to engage the heel 37 of the arm 29, when the arm 29 is rocked downwardly to a predetermined position. An overflow pipe 38 communicates with the container 12.

In operation, when the device is mounted over the radiator 9 in the manner indicated and the valve 27 moved from its seat, the float 28 being in its lower position, will maintain the valve head 33 in open position, so that water may enter the reservoir or container until the float is raised sufficiently to permit the spring 35 to function in moving the valve head 33 onto the seat 32.

The heat rising from the radiator will pass through the tubes 13 and serve to vaporize the water in the reservoir and the steam in the coils 16 and 17 will also assist in vaporizing, so that an efficient humidifying device is provided.

The invention is adapted for use either with direct or indirect radiation, thus affording a device which is universal in its application for use.

While I have illustrated and described the preferred form of my invention, I do not wish to limit myself to the precise form of structure shown but desire to avail myself of such variations and modifications as come within the scope of the appended claim.

Having thus described my invention, what I claim as new and desire to secure by Letters Patent is:

- 10 A humidifying device of the class described, comprising: a reservoir; a base on said reservoir; a plurality of tubes arranged in spaced relation projecting through said base and extending upwardly of said reservoir and terminating at their upper ends above the normal water level so as to communicate at both ends with the atmosphere; and a heating element extending into said reservoir at one end and projecting outwardly therefrom at the other and formed sinuous in said reservoir for winding among said tubes.
- 15
- 20

In testimony whereof I have signed the foregoing specification.
